FREQUENCY-SHIFT KEYING SYSTEM

Ernest W. Pappenfus, Cedar Rapids, Iowa, assignor to Collins Radio Company, Cedar Rapids, Iowa, a corporation of Iowa

Application May 25, 1949, Serial No. 95,217

15 Claims. (Cl. 250—36)

1
This invention relates to wave-signalling systems, and more especially it relates to systems of the keyed frequency-shift kind.

Various keyed frequency-shift transmitter arrangements have been proposed and used heretofore, employing a so-called reactance tube whose anode-cathode current conductivity is used to control the capacitive or inductive reactance of a tuned oscillatory circuit. Thus, in one arrangement that has been widely used, a relatively low frequency oscillator, for example at 200 kilocycles per second, has its generated frequency shifted by a reactance tube on either side of the mean or center frequency of the oscillator, which shifted frequencies represent respectively mark and space telegraph signals. While such an arrangement has been found satisfactory where there is a fixed range of frequency shift on either side of the center frequency, nevertheless, where the total shift requires substantial increase beyond that fixed amount, it has been difficult to produce the mark and space frequencies symmetrically and with equal frequency deviations from the center frequency. In fact, with such systems, comparatively elaborate center frequency adjustment and monitor means may be required. In an effort to overcome this disadvantage, it has been proposed heretofore to use a pair of reactance tubes connected for push-pull operation, one tube controlling the capacitive reactance and the other tube controlling the inductive reactance. However, since the signal keying potentials are usually in the nature of direct current voltages, considerable difficulty has been encountered with such push-pull arrangements, among which difficulties have been the instability and non-linearity of the frequency-shift response, and the requirement for using phase inversion at the input to the push-pull tubes.

Accordingly, one of the principal objects of this invention is to provide a frequency-shift arrangement having the advantages of the prior single reactance tube arrangement, and certain of the advantages of the prior push-pull reactance tube arrangement, but without the above-noted disadvantages of the prior arrangements.

A feature of the invention relates to a frequency-shift arrangement employing a pair of reactance control tubes, one of which has a steady direct current potential applied to its input control and the other of which has a signal-controlled variable direct current potential applied to its input control.

Another feature relates to a frequency-shift

arrangement employing a pair of grid-controlled electron tubes whose grids are excited respectively in leading and lagging phase quadrature with respect to the center frequency of the oscillator; and one of the tubes of the pair has applied to its input circuit a steady direct current voltage, while the other tube of the pair has applied to its input circuit the different direct current keying voltages representing respectively mark and space telegraph signals.

Another feature relates to a frequency-shift arrangement employing a pair of grid-controlled electron tubes whose grids are excited in opposite phases from the frequency-shift oscillator itself, one tube being excited in quadrature leading phase with respect to the oscillator and the other tube being excited in quadrature lagging phase with respect to the oscillator; in conjunction with means for applying direct current keying voltages to only one tube of the pair.

Another feature relates to a frequency-shiftable oscillator employing a pair of frequency-shift control tubes, whereby symmetry and linearity of the frequency shifts on either side of a center frequency, are obtained without requiring special phase inversion circuits between the direct current keying source and the input electrodes of said pair of tubes.

Another feature relates to a frequency-shiftable oscillator employing a pair of reactance control tubes feeding a common tube whose output phase with respect to the oscillator can be rendered either quadrature-leading or quadrature-lagging while applying direct current keying voltages to the input of only one of said pair of tubes.

A still further feature relates to the novel organization, arrangement and relative interconnection of parts which cooperate to provide an improved and stable frequency-shift keying transmitter.

In the drawing, which represents, by way of example, one preferred embodiment,

Fig. 1 is a schematic wiring and block diagram of a frequency-shift transmitter according to the invention.

Figs. 2, 3, 3a, 4, 5 and 5a, are respective vector diagrams explanatory of the operation of Fig. 1.

Referring to the drawing, the block 1 represents any well-known source of direct current keying control voltages, the keying portion of which is schematically represented by the two-position switch 2. When the arm 3 of this switch is on contact 4, zero or ground potential is ap-

2

plied to conductor 5. When the switch arm is on contact 6, a positive potential of "E" volts is applied to conductor 5. Associated with the source 1 are two control tubes V1, V2. These tubes may be of any well-known grid-controlled vacuum tube type, whose plate resistances or conductivities are respectively controlled by the direct current voltages applied to their control grids. The conductor 5 is connected through a suitable grid leak resistor 7 to the control grid 8 of tube V1. Thus, the grid 8 has applied thereto either a positive potential "E" representing, for example, a mark telegraph signal, or zero volts representing a space telegraph signal. The control grid 9 of tube V2 however, is connected through a suitable grid leak resistor 10 to a source of positive direct current potential 11, which is arranged so as to have a positive value which is equal to $E/2$. The anodes or plates 12, 13, of both tubes are connected through a suitable plate load resistor 14 to a suitable positive terminal 15 on the usual direct current plate power supply. The cathode 16 and the cathode 17 are returned to ground through a common cathode bias resistor 18 which may be shunted by a suitable by-pass condenser 19. The ungrounded end of resistor 18 is connected through an adjustable contact arm 20 to a resistor 21, connected directly between the cathodes 16 and 17.

By this manner of connecting the cathodes together and through the adjustable contact 20 and resistor 18, a certain amount of phase inversion is automatically effected in the common output of tubes V1 and V2. For example, when a positive potential "E" is applied to grid 8, the I. R. drop through resistance 18 biasses the cathode 17 in such a direction as to tend to reduce the plate current of tube V2. Likewise, when the grid 8 has zero voltage impressed thereon, the plate current of tube V2 produces a drop across resistance 18 which tends to reduce the plate current of tube V1.

The grids 8 and 9 are also arranged to be continuously excited by the carrier frequency, for example 200 kilocycles per second supplied respectively over conductors 22, 23, and through respective condensers 24, 25. This carrier frequency applied to conductors 22 and 23, is derived from the oscillator tube V4 which may be of any well-known grid-controlled vacuum tube type, provided that suitable feedback circuits cause it to generate normally the desired center frequency of for example 200 kilocycles per second. Merely by way of example, the tube V4 is shown as an oscillator of the Hartley type, wherein the high frequency inductance 26 has a portion 27 connected through condenser 28 between the control grid 29 and the cathode 30. While another section 28 of this inductance is connected between cathode 30 and the negative or grounded terminal of the conventional direct current plate power supply whose positive terminal 31 is connected through the inductance coil 32 to the plate 33. The oscillatory voltages which thus appear at the point 34 are applied simultaneously over two parallel paths 35, 36, through respective phase-shifting networks 37, 38. The network 37 which is interposed between the conductors 22 and 35, may comprise any well-known combination of shunt resistors 39, 40, and series condensers 41, 42, whereby the phase of the voltage waves at conductor 22 lead the phase of the corresponding voltage waves at the point 34 by 90° . Likewise, the network 38 may consist of any well-known combination of shunt condensers 43, 44, and series resistors 45, 46,

whereby the voltage waves at the conductor 23 lag in phase by 90° the phase of the waves at conductor 36. The vector and phase relation of the waves appearing respectively at point 34 and at 5 the grids of tubes V1 and V2, is illustrated in Fig. 2. From this figure it will be seen that the grids 8 and 9 are excited in 180° or opposite phase, and the phase of the waves at grid 8 leads the phase of the oscillations from tube V4 by 90° , whereas 10 the phase of the waves at grid 9 lags in phase by 90° the phase of the said oscillations from tube 4. The tubes V1 and V2 have a common plate load resistor 14 to produce thereacross a voltage wave which is the vector resultant of the voltage 15 waves at plates 12 and 13. If each tube has the same gain, that is if the direct current voltages applied to their grids are equal in magnitude, then the resultant wave voltage across resistor 14 is zero. In order to facilitate equalizing the gains 20 of both tubes, the arm 20 can be adjusted on the resistor 21. By means of adjusting contact arm on potentiometer resistor 21, the magnitude of leading lagging plate voltage V2P and V1P at plates 12 and 13 can be adjusted to equal magnitude as 25 shown in Fig. 4 when a voltage equal to $E/2$ is applied to grids 8 and 9 of V1 and V2. It should be observed that in the usual way, the plate voltage of each of the tubes V1, V2, is 180° out of phase with the excitation of its respective control grid. 30 This accounts for the fact that in Fig. 4 the voltage V2P leads the oscillator voltage V4, while the plate voltage V1P lags the oscillator voltage V4. When the system is thus adjusted, the voltage developed across the resistor 14 is zero so that no 35 radio frequency control voltage is applied to the grid 49 of tube V3, and the oscillator V4 generates at its selected center frequency. It will be observed that the oscillator V4 is provided with the usual tuning condenser 51 to tune the oscillator 40 to the desired center frequency, and the tube V3 being coupled to the tuned oscillatory circuit 26—57 through condenser 56, forms an effective control over the reactance of said tuned oscillatory circuit. In other words, tube V3 forms a 45 so-called reactance tube for the said tuned circuit. The plate load resistor 14 is coupled into condenser 47, and thence through adjustable potentiometer resistor 48 into the control grid 49 of another vacuum tube V3. The adjustable potentiometer resistor 48 serves as a gain or voltage 50 control determining the proportion of radio frequency voltage across resistor 14 which is fed to the control grid of V3. In this way the frequency shift effect of the system can be adjusted. 55 The cathode 50 of V3 is suitably by-passed by the cathode resistor 51 and the usual shunt condenser 52, so as to operate upon the linear portion of the grid-voltage plate-current characteristic curve of the tube. For this purpose, the plate 53 is connected through a suitable load resistor 54 to the positive terminal 55 on the direct current plate power supply. The load resistor 54 is connected through a suitable condenser 56 to the point 34 in the tuned circuit of the oscillator. 60 65 When the system has been thus initially balanced to cause oscillator V4 to generate at the center frequency, it is in readiness to receive the keying control voltages from the source 1. As above pointed out, the grid 8 is arranged to have either one or the other of two direct current voltage conditions applied thereto, namely zero voltage or voltage $+E$, while the grid 9 is arranged to have a steady positive voltage $E/2$ applied thereto. Assuming for example that a space signal, represented by zero volts, is applied from 70 75

source 1 to grid 8, it will be seen that the gain of tube V1 is less than the gain of tube V2, so that the vector relations between the two voltage waves applied to resistor 14 are as represented by the diagram of Fig. 3. Consequently, there is applied to the grid 49 a control voltage represented by the difference between the voltages V2P and V1P (Fig. 3). As a result, there appears across the resistor 54 a corresponding amplified voltage differential V3P, as represented by the vector diagram in Fig. 3a. This voltage wave lags the oscillator voltage by 90°, and has a predetermined magnitude, namely $(V2P - V1P)$ multiplied by the amplification factor of tube V3, which is effective through condenser 56 to cause the oscillator V4 to change its frequency to the lower or space frequency, for example 199.5 kilocycles per second. On the other hand, when a mark signal voltage +E is applied to grid 8, the corresponding vector relations in the plate voltage waves of tubes V1 and V2, are illustrated in Fig. 5. Thus the resultant differential voltage at the plate of tube V3 is then represented by the vector diagram of Fig. 5a. In this latter diagram, it will be seen that the resultant control voltage V3P leads the oscillator voltage V4, and is of a predetermined magnitude, so that it shifts the frequency of oscillator V4 to its upper shift frequency representing mark, for example 200.5. Thus it will be seen that an equal increase and decrease in frequency from the center frequency is brought about by applying +E volts or zero volts to grid 8, while maintaining the grid 9 steadily biassed with a voltage of E/2.

It has been found that with this arrangement, it is possible to eliminate the instability which is usually encountered where two tubes are operated in push-pull relation with the grids biassed by direct current keying potentials. Furthermore, by reason of the particular manner of connecting the cathode return circuits of tubes V1, V2, and the manner of exciting their grids, phase inversion of the carrier voltage occurs without the necessity of inverting the direct current keying voltages. The shifted frequency carrier can then be coupled through a condenser 58 to a suitable transmission channel such as a radio transmission channel, a wire line transmission channel, or the like.

While in the circuit disclosed in the drawing, the various tubes are shown as of the triode or single grid type, it will be understood that they may be of any plural grid type such as tetrodes, pentodes, or the like. Likewise, while the tubes V1 and V2 are shown with their electrodes enclosed in separate evacuated bulbs or envelopes, it will be understood that they can be enclosed in a single evacuated bulb or envelope to form any well-known dual triode electron tube.

While one particular embodiment has been disclosed herein, it will be understood that various changes and modifications may be made therein without departing from the spirit and scope of the invention.

What is claimed is:

1. A frequency-shift arrangement, comprising a variable frequency oscillator source whose frequency is to be shifted between predetermined limits, a pair of frequency control tubes for said oscillator, means to excite the grids of said control tubes from said oscillator in respective leading and lagging electrical phases with respect to the oscillator phase, and means to apply to the input of one control tube direct current keying potentials to shift the oscillator frequency.

2. A frequency-shift arrangement, comprising a variable frequency oscillator source whose frequency is to be shifted between predetermined limits, a pair of frequency control tubes for said oscillator, means to excite the grids of said control tubes from said oscillator and respectively in mutually opposite electrical phase and respectively in leading and lagging electrical phases with respect to the oscillator phase, and means to apply to the input of one control tube direct current keying potentials to shift the oscillator frequency.

3. A frequency-shift arrangement, comprising a variable frequency oscillator source whose frequency is to be shifted between predetermined limits, a pair of frequency control tubes for said oscillator, means to excite the grids of said tubes under control of said oscillator with respective quadrature leading and quadrature lagging electrical phases with respect to the oscillator electrical phase, and means to apply direct current control potentials to the grids of said tubes to correspondingly shift the oscillator frequency.

4. A frequency-shift arrangement according to claim 3, in which means are provided for applying a steady direct current potential to the grid of one tube and for applying a controllable direct current keying potential to the grid of the other tube.

5. A frequency-shift arrangement according to claim 4, in which said steady direct current potential is approximately one-half the difference between the said controllable direct current keying potentials.

6. A frequency-shift arrangement, comprising an oscillator whose frequency is to be shifted between predetermined limits, electron tube means having a pair of control grids, a common output circuit for said tube means, means to excite one of said control grids from the oscillator through a phase-shifting network, means to excite the other control grid from the oscillator through another phase-shifting network, said networks being mutually proportioned so that the excitations of said grids are respectively in quadrature-leading phase and quadrature-lagging phase with respect to the oscillator phase, means to apply direct current gain control potentials to said grids to develop in said common output circuit of said electron tube means a resultant voltage proportional to the difference in magnitude of the potentials applied to said grids, and means to apply said resultant voltage to shift the frequency of said oscillator in accordance with the difference between said applied direct current potentials.

7. A frequency-shift arrangement according to claim 6, in which the direct current potentials applied to one of said control grids varies between predetermined lower and upper limits corresponding to keying signals, and the direct current potential applied to the other of said control grids is one-half the difference of the voltages applied to said one of said control grids.

8. A frequency-shift arrangement according to claim 6, in which said electron tube means also includes a pair of cathodes and a pair of anodes, each cathode and anode cooperating with a corresponding one of said control grids, and a common output circuit for said anodes for developing said resultant voltage.

9. A frequency-shift arrangement according to claim 8, in which means are provided for applying said resultant voltage to the control grid of a reactance control tube, and circuit connections for applying the variable plate resistance of said

electron tube to correspondingly shift the oscillator frequency.

10. A frequency-shift arrangement according to claim 9, in which said reactance tube has its control grid connected to the output circuit of said electron tube means through a potentiometer for the purpose described.

11. An arrangement for controlling the frequency of an oscillator, comprising a reactance tube coupled to the frequency-determining portion of said oscillator, electron tube means for controlling said reactance tube said electron tube means comprising a pair of control grids having a common output circuit and individual input circuits connected respectively to said grids, means to excite the input circuits of said tubes from said oscillator, means to phase-shift the excitation of one input circuit to quadrature-leading phase with respect to the oscillator, means to phase-shift the excitation of the other input circuit to quadrature-lagging phase with respect to the oscillator, means to apply direct current gain control potentials to said grids, and circuit means connecting the said common output circuit to the control grid of said reactance tube.

12. An oscillator control arrangement according to claim 11, in which the gain control potential applied to one grid of said pair is maintained constant, and the gain control potential applied to the other grid of the pair is arranged to be varied to control the oscillator frequency.

5

10

15

20

25

30

13. An oscillator control arrangement according to claim 11, in which the gain control potential applied to one grid of the pair is adjustable between predetermined limits, and the gain control potential applied to the other grid of the pair has a magnitude approximately equal to the mean between said limits.

14. An oscillator control arrangement according to claim 11, in which said electron tube means comprises a pair of grid-controlled electron tubes having their cathodes returned to ground through a common cathode load resistor.

15. An oscillator control arrangement according to claim 11, in which said electron tube means comprises a pair of grid-controlled electron tubes having their cathodes connected together through a potentiometer-resistor, the contact arm of said potentiometer being connected to ground through a cathode-load resistor which is common to both tubes.
